US00D640040S

(12) United States Design Patent
Martin

(10) Patent No.: US D640,040 S
(45) Date of Patent: * Jun. 21, 2011

(54) PENIS AND TESTICLES ENHANCEMENT SUPPORT DEVICE

(76) Inventor: Bruce R. Martin, Boca Raton, FL (US)

() Term: 14 Years

(21) Appl. No.: 29/382,247

(22) Filed: Dec. 30, 2010

(51) LOC (9) Cl. 24-04

(52) U.S. Cl. D2/711; D24/190

(58) Field of Classification Search D2/712, D2/713, 714, 715, 716, 717, 728, 731, 732, D2/738, 742, 743, 744, 747, 860; D24/189, D24/190, 191; 2/69, 70, 71, 72, 73, 78.1, 2/78.2, 78.3, 78.4, 134, 227, 234, 228, 237, 2/311, 400, 401, 402, 403, 405, 406, 407, 2/408; 128/96.1, 842, 844; 600/38, 39; 602/68, 602/69, 70, 73; 604/347, 349, 352

(57) CLAIM

The ornamental design for a penis and testicles enhancement support device, as shown and described.

DESCRIPTION

FIG. 1 is a front elevation view of a penis and testicles enhancement support device showing my new design;

FIG. 2 is a rear elevation view thereof;

FIG. 3 is a right side elevation view thereof, the opposite side being a mirror image of that shown.

FIG. 4 is a top plan view thereof; and,

FIG. 5 is a bottom plan view thereof.
